US00D858340S

(12) **United States Design Patent** (10) Patent No.: **US D858,340 S**
(45) Date of Patent: ** Sep. 3, 2019

(54) **WRISTBAND WITH FOOT**

(71) Applicant: **Precision Dynamics Corporation**, Valencia, CA (US)

(72) Inventors: **Ron Ennis**, Los Angeles, CA (US); **James Kopitzke**, Valencia, CA (US)

(73) Assignee: **Precision Dynamics Corporaiton**, Valencia, CA (US)

(**) Term: **15 Years**

(21) Appl. No.: **29/611,880**

(22) Filed: **Jul. 26, 2017**

(51) LOC (12) Cl. **11-01**

(52) U.S. Cl.

USPC **D11/3**

(58) **Field of Classification Search**

USPC D11/3-5; D19/1-8; D20/22, 27, 99; D24/189
